UNITED STATES PATENT OFFICE.

ALEXANDER McDONALD, OF DULUTH, MINNESOTA.

LIQUID-RECEPTACLE.

1,300,432.

Specification of Letters Patent. Patented Apr. 15, 1919.

Application filed February 11, 1918. Serial No. 216,582.

To all whom it may concern:

Be it known that I, ALEXANDER McDONALD, a citizen of the United States, residing at Duluth, in the county of St. Louis 5 and State of Minnesota, have invented certain new and useful Improvements in Liquid-Receptacles, of which the following is a specification, reference being had therein to the accompanying drawing.

This invention relates to a combined liquid container, cooler and stand and has special reference to a rotatable device of this character having a plurality of radially arranged compartments or containers about an 15 axially disposed cooling compartment.

The principal objects of the invention are to provide a simple container of this type in which the constituent parts thereof are readily separable for cleansing purposes and 20 one of practical and efficient construction.

Other objects and advantages of the novel construction will appear in the further description of the invention.

In the accompanying drawings forming 25 part of this application and in which like reference characters indicate like parts:

Figure 1 is a central vertical section of a receptacle embodying my invention, and:

Fig. 2 is a transverse sectional view on 30 the line 2—2 Fig. 1.

1 represents the base of the stand, being circular in plan view and having an upwardly extending gracefully shaped central portion 2 terminating in a flat disk-like member 3. Centrally within the portion 3 is screw threadedly mounted the axial tubular shaft 4, there being an enlarged central boss 5 formed on the member 3 for suitable reception of the shaft 4. Within the top of 40 the shaft 4 is screw threadedly mounted a conically shaped plug 6 forming a pivotal point upon which the balance of the device is pivotally supported. 7 represents a cap surmounting the plug 6 and the upper end 45 of the shaft 4 and from which the rotatable portion of the device is suspended by the tube 8 surrounding the shaft 4 and being screw threadedly attached within the lower end of the cap 7.

To the lower end of the tube 8 is secured 50 in any desired manner the circular bottom member 9 of the central cooling receptacle 13 and which also constitutes the supporting shelf for the liquid receptacles by that portion extending beyond the central receptacle.

About the circumferential edge of the member 9 is a rim or flange extending both above and below the member as at 10 and 11 respectively. The extension 10 acts as a guard to the lower end of the individual 60 containers 12 and the depending extension 11 acts as a covering to the space intermediate of the members 3 and 9 as they are spaced apart to make room for the pipe connection indicated at 14 for draining the 65 waste liquid from the cooling receptacle 13, said pipe having a suitable faucet or cock 15 on the outer end thereof through which the liquid may be drawn at times when necessary. 70

The cooling receptacle is made star-shaped in cross section and as a preferable form I have shown same as likened to a six pointed star, each point of which is surrounded by and extends within one of the 75 liquid containers 12, the inner wall of each of which is substantially the form of the letter W.

I am aware that radially disposed containers have been arranged about a star-shaped axial cooling receptacle, but not having the points of the cooling receptacle extending within the center of the radial containers and therefore considered lacking in cooling efficiency in respect to the liquid 85 within the containers. Adjacent the upper end of the tube 8, fastened thereto and extending radially therefrom are rigid braces 17 fixed to the outer end of the inwardly extending angular portions of the side walls 90 of the cooling receptacle for the purpose of strengthening same. The upper end of the cooling receptacle is entirely open for the convenient reception of ice such as commonly used in similar devices. 95

A removable ring like cover 18 rests upon and covers the upper ends of the containers, it having a central cylindrical barrel portion 19, which fits inside of the innermost angular portions of the walls of the 100 cooling chamber. A depending annular flange 20 is formed integral with the outer edges of the cover and serves to hold the containers in place when mounted upon same. 105

A hole and stopper in the cover as indicated at 21 is provided for filling the containers and through which hole any one of the latter may be conveniently filled when desired as the cover may be rotated 110

in either direction for such purpose and the upper ends of all of the containers are entirely open as indicated.

Above the portion 19 is fitted a second cover 22 which is held tightly thereupon by the bolt 23 being screwed into the upper end of the cap 7, the opposite end of the bolt having applied thereto a suitable decorative nut 24 which is drawn down tightly upon the second cover when the two covers are in place and the complete device properly assembled.

I have shown the bottom 25 of the containers as being inclined downwardly and each container having a spring push faucet fixed thereto through which the liquid in the container is drawn off. However, any desired style of faucet may be employed.

Having thus described my invention, what I claim as new and desire to secure by Letters Patent, is:

1. The combination with a stand having a rotatable axial cooling chamber star shaped in horizontal cross section, of a plurality of independent removable circumferential liquid containers having their sides abutting each other and their innermost walls each surrounding a point of the star shaped chamber.

2. The combination with a stand comprising a rotatable central cooling chamber having a centrally disposed tube therein and containers radially disposed thereabout, of a hollow axle shaft extending upwardly from the center of the stand into the tube of the cooling chamber, a pivotal plug attached to the upper end of the tube, a cap

pivotsally mounted upon the plug supporting all of the rotatable portion of the device, and a cover common to the cooling chamber and containers carried by the cap.

3. In combination, a stand, an upright central shaft fixed to the stand, a tubular shaft surrounding the fixed shaft and pivotally supported thereupon, a circular bottom member fixed to the lower end of the tubular shaft and forming the bottom of a central cooling receptacle, said bottom extending beyond the cooling receptacle and forming an annular supporting shelf, radially disposed liquid containers carried by said shelf and a rotatable cover acting as a closure for the containers and the cooling receptacle.

4. The combination with a device of the character described comprising a central cooling receptacle having an axial supporting member therein, and a plurality of radially disposed containers about the cooling receptacle, of a rotatable cover for the device comprising an annular section covering the containers, a vertically disposed axial cylindrical portion fixed to the annular section and extending somewhat above and below same and a second cover section resting upon and acting as a closure to the cylindrical portion substantially as described.

In testimony whereof I hereunto affix my signature in the presence of two witnesses.

ALEXANDER McDONALD.
